His Attorney

UNITED STATES PATENT OFFICE.

MOSES WOLFE, OF NEW YORK, N. Y.

DESIGN FOR AN EMBLEM OR SIMILAR ARTICLE OF JEWELRY.

47,839.

Specification for Design.

Patented Sept. 14, 1915.

Application filed June 30, 1915. Serial No. 27,390. Term of patent 3½ years.

To all whom it may concern:

Be it known that I, MOSES WOLFE, a citizen of the United States, residing at the city of New York, in the county of New York, State of New York, have invented a new, original, and ornamental Design for an Emblem or Similar Article of Jewelry, of which the following is a specification, reference being had to the accompanying drawing, forming part thereof.

The figure is a plan view of an emblem or similar article of jewelry showing my new design.

I claim:

The ornamental design for an emblem or similar article of jewelry as shown.

MOSES WOLFE.
